UNITED STATES PATENT OFFICE.

DANIEL Y. MILLER, OF HUNTSVILLE, ILLINOIS.

IMPROVEMENT IN SCAFFOLDS.

Specification forming part of Letters Patent No. 139,726, dated June 10, 1873; application filed March 29, 1873.

To all whom it may concern:

Be it known that I, DANIEL Y. MILLER, of Huntsville, in the county of Schuyler and State of Illinois, have invented a new and Improved Scaffold, of which the following is a specification:

In the accompanying drawing, Figure 1, represents a front view of my improved scaffold; Fig. 2, a vertical transverse section of the same on the line *c c*, Fig. 1. Figs. 3 and 4 are detail sections of the connecting-parts of the supports; Fig. 5, pieces applied to the platform for resting against the walls.

Similar letters of reference indicate corresponding parts.

The object of my invention is to construct a scaffold for the use of painters, carpenters, and others, which may be easily set up and taken to pieces and readily transported. A platform may be raised or lowered at will, the whole structure being simple, strong, and durable, and not too expensive. The connection of the different parts is accomplished in a firm and substantial manner. My invention consists of two main supports resting on standards and composed of several pieces, connected by strong staples, the uppermost pieces suspending, by block-and-tackle arrangement, an adjustable platform, which may be elevated to the full height of the supports.

In the drawings, *A* represents the standards, which form the base of the supports, consisting of two strong pieces, *a*, of wood or other suitable material, with sharp points *b* to rest in the ground, and a strong band, *d*, of iron or other metal. The pieces *a* incline towards each other under a suitable angle, and are bolted to band *d*, leaving a recess between them for the admission of the wedge-like end of the connecting piece *B* of the supports. Piece *B* fits closely between the braces *a*, and has a band, *e*, bolted to it, with side extensions or shoes to slip over the ends of braces *a* and form a rigid and strong connection with them. The upper end of piece *B* is beveled sidewise, having also a band or staple, *f*, bolted to it, fitting over the beveled ends of piece *C*, which is constructed in similar manner with beveled ends and staples,

allowing an extension and joining of as many pieces as may be required. The pieces *C*, in connection with pieces *B* and standards *A*, form strong and continuous supports, which may easily be taken to pieces and set up again, and be removed without difficulty. The uppermost piece *C* of each support has a strong staple, *g*, to which is suspended the block-and-tackle arrangement *D*, which connects by rope *E* with platform *F*. Platform *F* is constructed of boards resting on lateral pieces *h*, to which the bails *i* are attached, which connect in a suitable manner with ropes *E*. The ends of pieces *h*, toward the wall or other object, are supplied with guide-rollers *K*, which prevent the dragging, scraping, or otherwise injuring of the wall by the platform. By means of a slotted plate, *l*, into which a projecting pin may be adjusted, platform *F* is kept steadily in position without danger of tilting. In case substantial wooden or iron bails *i* cannot be obtained, so that ropes or other unsteady materials are substituted in their place, the pieces *G*, Fig. 5, are applied to the part of the platform nearest the wall, bolted through the middle part perpendicularly to the platform, the projecting beveled points *m* resting on the wall to prevent the platform from tilting. The ropes *E* are of sufficient length to be operated either from the ground or the platform. The whole scaffold may also serve as a means of escape in case of fire.

Having thus described my invention, I claim as new and desire to secure by Letters Patent—

1. In combination with the standard *A*, formed of the short bars *a* beveled at their upper ends and pivoted to the band *D*, the bars or pieces *B*, and band *e*, as described, whereby said parts *A* *B* are adapted to be connected, as set forth.

2. The platform *F*, having lateral pieces *h* with guide-rollers *K*, and plate *l* for guard-pin as described.

DANIEL Y. MILLER.
